KNITTING MACHINE

Kenneth Howie, Norristown, Pa., assignor to
Wildman Mfg. Co., Norristown, Pa., a corpora-
tion of Pennsylvania

Original application September 26, 1940, Serial
No. 358,533. Divided and this application July
2, 1941, Serial No. 400,838

5 Claims. (Cl. 66—102)

The invention relates to pressers for the beards of spring beard needles.

While the invention is illustrated in connection with a knitting machine of the full fashioned type, it is not limited in this respect.

It is sometimes desirable that only certain of the needles be pressed, and moreover, that they be pressed at a point above the level where the usual pressing operation takes place. The present invention relates to a presser implement by which the needle beard may be pressed at a high level when it is desired to start fabric on bare needles or for other purposes.

In the drawing:

Figure 1 is a transverse sectional view through a machine at the sinker head portion thereof.

Fig. 2 is a view similar to Fig. 1, but with the parts in a different position from that of Fig. 1.

Fig. 3 is a plan view of the presser element.

Fig. 4 is a plan view of the sinker and Fig. 5 is a plan view of a divider.

Fig. 6 is a side view of the presser element.

Fig. 7 shows a part of the sinker head base.

The needles 1 are of the spring beard type, and are supported in the usual manner by clamping their lower ends in a needle bar (not shown). These needles are disposed in a straight line, as the machine chosen to illustrate the invention is of the full fashioned type employed for knitting hosiery.

Sinkers are indicated in dotted lines at 2. The dividers are not indicated in assembly but they are arranged as is well known.

The numeral 5 indicates the usual sinker head base and 7 the sinker head cover. These parts guide the sinkers and dividers.

The sinkers, as usual, are made of thin strip material and they are reinforced by plates 8 and 9 as in Fig. 4. Jacks 10 drive the sinkers.

The dividers 3 are of thin strip material throughout their lengths, and are not reinforced. Both the dividers 3 and the sinkers 2 are provided at their rearward ends with upstanding butts which may be engaged by the catch bar 11. The presser element 12 of the invention is best shown in Figs. 3 and 6. This presser element 12 is made up of a thin strip portion 13 to which is attached a headpiece 14. One side of the headpiece 14 is recessed to a depth to just receive the strip portion 13, so that the one side of the presser element will be flush throughout its length.

The headpiece 14 of the presser element 12 is as wide as the space between the thin strip portions of the adjacent sinkers and divider. By

lying in and filling this space, the headpiece is guided against lateral movement by the sinker and divider on opposite sides thereof. The thin strip portion 13 is only as wide as the small space left between the adjacent divider 3 and the reinforcing plate 9 of the adjacent sinker 2. The rearward portion of the presser element 12 is therefore guided against lateral movement. By being thin, the strip portion 13 not pass through the narrow space between the divider and the reinforcing plate 9 of the sinker, but passes as well through the narrow space between the upper ends of the jacks 10.

The headpiece 14 of the presser element 12, by being as wide as the space between the forward thin portions of the adjoining sinker and divider, presents a broad face 15 for contact with the beard of the needle. The wide breadth of this face 15 is made possible by taking advantage of the fact that the reinforcing plate 9 does not extend to the forward end of the sinker 2.

The lower edge of the headpiece, forward of the attachment to the strip portion 13, is cut away, providing an inclined edge 16. At its upper forward edge, the headpiece is provided with a raised part 17. The height of this raised part is approximately the same as the depth of the cut away part on the lower edge of the headpiece. The rearward edge of the raised part 17 is inclined to form a cam surface 18.

The inclined surface 16 of each presser element cooperates with the rearward inclined surface 21 of one of the projections 20 present between every sinker and divider. These projections 20 extend upwardly from the sinker head base 5 and are contacted at their forward face 23 by the beard of the needles in plain knitting. As the presser element is advanced in a direction toward the needle bed, from its position of Fig. 1, its surface 16 will bear against the surface 21 of projection 20. Continued forward movement of the presser element will cause the headpiece 14 to be cammed upwardly, so that when it is in its fully advanced position of Fig. 2, it will lie above the level which it occupies when it is in its retracted position of Fig. 1.

When the presser element is retracted, the inclined surface 18 of the headpiece will contact the forward face 19 of the cover 7 of the sinker head and cam the presser element downwardly to the lower position it occupies when it is retracted. It will be clear that for this upward and downward camming action to occur, the

surface 21 must lie to the rear of the edge 19, a distance which at the greatest is the horizontal distance from surface 18 to surface 16 of the presser element.

It may be observed that the presser element is incapable of up or down movement both when in its advanced and in its retracted position. This is because the vertical distance from the top of the raised part 17 to the lower edge 22 of the presser element is the same as the height of the space between the sinker head base 5 and cover 7, and because the heights of the projections 17 and 20 are equal and the same as the depth of the cut-away portion providing the surface 16.

To drive the presser elements 12 forward and backward, they are made elongated to extend to the rear of the sinkers and dividers. At their rearwardmost portions, they are made of increased height, and are formed with a notch 24. The lower end of a blade 25 lies in this slot, and the upper end of this blade is secured to a rock shaft 26. Rotation of the rock shaft is preferably under control of a pattern mechanism, so that the presser elements will be automatically advanced or retracted. To limit the retracting movement of the presser element, it may be provided on its lower edge 22 with a lug 27 which will abut against a plate 28 which extends along the machine.

The plate 28 also serves as a rest to support the rearwardmost ends of the presser elements. The presser elements, therefore, do not bear upon the sinker head except at their wide head portions 14.

The presser elements normally lie in their retracted position, as shown in Fig. 1, so that they are entirely inactive during usual knitting operations. At the time they are to be employed, they are urged forward by the blade 25 to the position of Fig. 2. The upward movement of each presser element, due to the cam surfaces 16 and 21, places the face 15 of that presser at such a high point that the beard of the needle in line therewith is pressed to closed position before the yarn upon the needle has entered the beard. The yarn consequently passes over the beard and is cast off of the needle as the needle moves downward. When the presser element is then retracted, it is forced downwardly by the action of surfaces 18 and 19, so that the position of Fig. 1 is resumed.

The location of the head of the presser element at a high position when it is advanced and at a low position when it is retracted is an important feature of the invention. By lowering it when it is retracted, it is entirely out of the way of the movement of the yarn carriers (not shown) which pass back and forth immediately in front of the surface 19. By raising the head of the presser element when it is in its forward active position, its face 15 will press the beard of the needle above the sinker throat, and therefore prior to the entry of the yarn upon the needle under the beard of the needle, as has been noted.

A particular use of the presser elements of this invention is to assist in starting up fabric on bare needles. For this purpose, a presser element is provided for every other one of the needles upon which the fabric is to be started. Immediately after the new yarn has been laid against the bare needles by the yarn carrier, the presser elements are advanced and the yarn will

therefore be pressed off every other needle as the needles move downward through their knitting stroke. The yarn will then pass to the front and to the rear of successive needles, so that the next yarn laid down will be knit into loops upon all the needles. Regular knitting will thereafter occur in the usual manner.

As an example of starting knitting on bare needles, the production of a complete lady's hose upon a single machine may be considered. This may be accomplished by casting off the heel tabs after they have been knit, and then returning to the needles the instep portion of the fabric. Knitting must then occur beyond the width of the instep to make up the full width of the sole. The presser elements of the invention are accordingly provided for every other one of the needles which lie beyond the instep of the fabric, on both sides of the fabric.

The presser elements of the invention may also be employed to cause drop stitches for fancy work at any portion of the fabric by associating one of the presser elements with each of the needles upon which a drop stitch is to be made.

This application is a division of that filed Sept. 26, 1940, Ser. No. 358,533.

I claim:

1. A presser element for spring beard knitting needles comprising an elongated strip-like portion and a widened head portion of uniform width from top to bottom of the element, said head portion presenting a pressing face at an extreme end of the element for substantially the full width and height of the head portion, a side face of the element being flush from end to end of the element.

2. A presser element for spring beard knitting needles comprising an elongated strip-like portion and a widened head portion of uniform width from top to bottom of the element, said head portion presenting a pressing face at an extreme end of the element for substantially the full width and length of the head portion, said head portion having on its underside a cam surface inclining upwardly and forwardly toward the pressing face of the element.

3. A presser element for spring beard knitting needles comprising an elongated strip-like portion and a widened head portion of uniform width from top to bottom of the element, said head portion presenting a pressing face at an extreme end of the element for substantially the full width and length of the head portion, said head portion having on its underside a cam surface inclining upwardly and forwardly of the element, and said head portion having a projection on its forward upperside to provide a cam surface inclining downwardly and rearwardly away from the pressing face of the element.

4. A presser element for a spring beard needle of a full fashioned knitting machine having a stem portion and a head portion, said head portion presenting a pressing face at an extreme end of the element, said presser having on the under side of its head portion and at a point removed from said extreme end a cam surface inclining upwardly toward the pressing face for raising the presser to press the needle beard at a level higher than normal.

5. A presser element according to claim 4 having on the upper side of its head portion a projection with a cam surface inclining downwardly and rearwardly away from said pressing face.
